CLAIM

The ornamental design for a detachable front wheel for a boat, as shown and described.

DESCRIPTION

FIG. 1 is a right side elevational view of a detachable front wheel for a boat showing my new design, the left side elevational view being a mirror image of that shown;
FIG. 2 is a front elevational view thereof;
FIG. 3 is a rear elevational view thereof;
FIG. 4 is a top plan view thereof;
FIG. 5 is a bottom plan view thereof.

FIG. 1

FIG. 2

FIG. 3

FIG. 4

FIG. 5
